CLAIM

The ornamental design for heat exchanger slide rails, as shown and described.

DESCRIPTION

FIG. 1 is a front perspective view of heat exchanger slide rails showing our new design.

FIG. 2 is a front view thereof.

FIG. 3 is a rear view thereof.

FIG. 4 is a top view of the right heat exchanger slide rail as shown in FIG. 2.

FIG. 5 is a bottom view of the right heat exchanger slide rail as shown in FIG. 2.

FIG. 6 is a front view of the right heat exchanger slide rail as shown in FIG. 2 and being magnified for clarity of illustration.

FIG. 7 is a rear view of the right heat exchanger slide rail as shown in FIG. 2 and being magnified for clarity of illustration.

FIG. 8 is a left view of the right heat exchanger slide rail as shown in FIG. 2.

FIG. 9 is a right view of the right heat exchanger slide rail as shown in FIG. 2.

FIG. 10 is a top view of the left heat exchanger slide rail as shown in FIG. 2.

FIG. 11 is a bottom view of the left heat exchanger slide rail as shown in FIG. 2.

FIG. 12 is a front view of the left heat exchanger slide rail as shown in FIG. 2 and being magnified for clarity of illustration.

FIG. 13 is a rear view of the left heat exchanger slide rail as shown in FIG. 2 and being magnified for clarity of illustration.

FIG. 14 is a left view of the left heat exchanger slide rail as shown in FIG. 2.

FIG. 15 is a right view of the left heat exchanger slide rail as shown in FIG. 2; and,

FIG. 16 is an additional rear view thereof.
